UNITED STATES PATENT OFFICE.

GEORGE W. SMITH, OF ROCKFORD, ILLINOIS, ASSIGNOR TO INGERSOLL MILLING MACHINE COMPANY, OF ROCKFORD, ILLINOIS, A CORPORATION OF ILLINOIS.

FACE-MILL GRINDER.

No. 856,662.

Specification of Letters Patent.

Patented June 11, 1907.

Application filed August 2, 1905. Serial No. 272,441.

To all whom it may concern:

Be it known that I, GEORGE W. SMITH, a citizen of the United States, residing at Rockford, in the county of Winnebago and State of Illinois, have invented certain new and useful Improvements in Face-Mill Grinders, of which the following is a specification.

The object of this invention is to construct a machine for grinding the knives of a milling-machine, and in which the knives are ground from their cutting edge toward the heel.

In the accompanying drawings. Figure 1 is a plan view of my improved face-mill grinder. Fig. 2 is a vertical section on dotted line *a* Fig. 1. Figs. 3 and 4 are elevations. Fig. 5 is a vertical section through the base on dotted line *b* Fig. 3. Fig. 6 is a transverse section on dotted line *c* Fig. 2.

The base 1 has a cylindrical column 2 which is hollow thereby forming a space 3. The upper end of the column is closed with the exception of the central opening 4. A rotary water pump 5 is supported by the base, and is driven in any suitable manner. The suction end of this pump has a communication with the lower portion of the space 3. A hose 6 or other connection is made with the pump and having its discharge end located in proper relation with the knife being ground. The water returns into the space 3 by passing through the opening 4. The column 2 has a race-way 7 within which are located balls 8. From the column 2 extends an arm 9, which supports a screw 10. Around the column 2 is located a collar 11 from which extends a bracket 12. The lower face of this collar rests on the balls 8 thereby forming an anti-friction connection between the collar and its support. The lower portion of this collar is formed with a T shaped groove 13 within which are located two T headed bolts 14 and 15. Each of the bolts 14 and 15 supports a block 16 which are clamped in connection with the collar by the nuts 17. By loosening the nuts 17 the blocks 16 can be adjusted around the collar so that in the oscillations of the collar they will strike the screw 10 thereby limiting the movement of the collar. This collar is ver-

tically slotted and by means of the bolts 18, it may be clamped around the column 2 and held stationary.

The bracket 12 supported by the collar 11, has an upper horizontally disposed plate 19. On this plate 19 is located a swivel 20 which is clamped in position by the screws 21. This swivel has a slide-way 22 and also supports a screw 23. A slide 24 is supported by the swivel 20 with which the screw 23 engages, thereby moving the slide in the lengthwise direction of the slide-way 22. The slide 24 is provided with a guide-way 25 which is located transverse to the length of the slide. A slide 26 is located in the guide-way 25 and to which is connected an arm 27 provided with a series of notches 28 in the under face of its free end. A lever 29 has a pivotal connection with the slide 24 and has a projection extending from its inner face with which the arm 27 engages.

The slide 26 supports a grinding wheel carriage consisting of a base 30 and two ears 31 and 32 each of which is provided with a curved slot 33. This grinding wheel carriage is pivotally connected with the slide 26 by the screw 34 and the upper face of the slide is provided with a T shaped groove 35. Two T headed bolts 36 have their heads located in the groove 35 and their shanks extending upward through the grinding-wheel carriage and receiving nuts on their projecting ends. By this connection of the grinding wheel carriage with the slide 26, the carriage can be turned on its pivotal center, and clamped in its adjusted position. A bearing for the grinding wheel is composed of the two bearing surfaces 37 and 38 connected by a branch 39. This branch has a central opening through which a stud 40 passes, thereby connecting it in a pivotal manner with the grinding wheel carriage. Bolts 41 pass through the branch 39 and the two curved slots 33 of the grinding wheel carriage which clamp the grinding wheel bearing in connection with the grinding wheel carriage in an adjustable manner. A shaft 42 is supported in the two bearings 37 and 38, and a pulley 43 has a connection with the shaft, and is located between the bearings. A grinding wheel 44 has a connection with one end of

the shaft 42 and a grinding wheel 45 has a connection with the other end of the shaft.

To the upper end of the column 2 is secured a bracket 46 which is provided with a guide-way 47. A slide 48 is supported by the bracket and a screw 49 engages the slide and is rotated by the hand wheel 50. The slide 48 supports a swivel-base 51 which is moved by a screw operated by the hand-wheel 52. This swivel-base 51 supports a swivel 53 on the center 54. The upper face of the swivel-base is provided with a T shaped circular groove 55. A bolt 56 has its head located in the groove 55 and its shank portion passes through an opening in the swivel, and by means of the nut 57 the swivel can be clamped in connection with the swivel-base, after the swivel has been properly adjusted. The swivel 53 has its upper portion cylindrical and is provided with a vertical lengthwise central opening 58. Around the cylindrical portion of the swivel is located a cutter-head sleeve 59 which has a vertical slot, and by means of the bolts 60 passing through the flanges 61 the sleeve can be clamped around the swivel. A screw 62 has a screw-thread connection with the sleeve 59, its lower end resting on a ledge 63 extending from the lower portion of the swivel. The upper end of this screw is in crank handle form. By means of this screw 62 the cutter-head sleeve can be raised and lowered in its connection with the cylindrical portion of the swivel. The cutter-head sleeve has a cut-away portion on opposite faces, corresponding with the vertical opening of the swivel. From the cutter-head sleeve extend two perforated ears 64 and 65. Two screws 66 and 67 are supported by the cutter-head sleeve. A support 68 for the cutter spindle has a pivotal connection with the ears 69 by stud-bolts supported by the ears. The other end of this cutter spindle support is located between the screws 66 and 67 by means of which it may be rocked on its pivotal connection with the cutter-head sleeve. This cutter-spindle support has a central lengthwise opening.

A cutter-spindle 70 has one end provided with an enlargement 71 and its other end 72 is externally screw-threaded. This spindle has a section 73 externally screw-threaded. On the cutter-spindle is located a loose friction element 74 which supports a series of spacing disks 75 by the bolts 76 passing through the disks and entering the head of the loose friction element.

A tight friction element 77 has a feather 89 connecting it with the cutter-spindle, and four handles have a connection with the tight friction element. A lock-nut 78 has a screw-threaded connection with the cutter-spindle and bears against the tight friction element thereby forcing it in contact with the loose friction element in order that the loose friction

element may be turned by the handles which turns the cutter-spindle at the same time.

A cutter-head 79 supporting a series of knives 80 is connected to a shank 81 which is forced into the lengthwise opening 82 in the cutter-spindle.

From the cutter-spindle support 68 extends an arm 83, to which is pivoted a spacing disk dog 84 intermediate its ends. To one section of this dog is slidably connected a finger 85 having a pointed end adapted to enter the notches of the spacing disks. A handle 86 is provided for this end of the dog. A spring 87 is located between one end of the dog and the arm 88. This spring serves to hold the finger in some one of the notches of the spacing disks in a yielding manner.

The various spacing-disks are differently spaced with peripheral notches so that some one disk will have the same number of notches as the cutter-head has knives and by placing the finger alternately in the notches of a given disk, the various knives of the cutter-head will be presented to the grinding wheel. The finger in its engagement with the spacing disks will hold the cutter-head stationary while a given knife is being ground. By means of the screw the cutter-head can be raised and lowered bodily so as to present the knife properly to the grinding wheel. By means of the swivel, the cutter-head can be turned to present the face of the knives to the grinding wheel. By means of the screws 66 and 67 the cutter-head can be tipped on its pivotal centers if it be necessary to grind the knives at a different angle.

The grinding wheels 44 and 45 can be turned axially on the center 40 in order to present them at any desired angle to the knives. By means of the lever 29 the grinding wheels can be moved across the cutting edge of the knives. The hand-wheel 23 moves the grinding wheel toward and from the knives according as the diameter of the cutter-head varies. The corner of the cutting edge of the knives can be rounded by loosening the collar so that it may oscillate around the column and the adjustable blocks 16 set to strike the arm 9, thereby limiting the oscillations of the collar. The grinding wheels are rotated in the direction indicated by the arrows thereon, which will grind the knives from their cutting edge to the back. By this method of grinding the knives, the cutting edge remains cool, and the temper will not be drawn.

I claim as my invention,

1. In a face mill grinder, the combination of a base having a cylindrical column, a bracket having a free swivel engagement with the column, an arm extending from the base, two stops adjustably supported by the bracket toward and from the arm, a grinding wheel supported by the bracket, and a

cutter-head support connected with the column.

2. In a face mill grinder the combination of a base having a cylindrical column, a bracket having a swivel engagement with the column, a slide supported by the bracket, a cross-slide supported by the bracket slide, a lever connection with the bracket slide, an arm adjustably connecting the cross-slide 10 with the lever, and a grindir z wheel support having a swivel connection with the cross-slide.

3. In a face mill grinder, the combination of a base having a vertical column, a bracket supported by the column, a support having a swivel connection with the bracket, a cutter-head sleeve capable of being clamped around the swiveled support, means for vertically adjusting the cutter-head sleeve, and 15 a cutter-spindle support connected with the cutter-head sleeve.

4. In a face mill grinder, the combination of a base having a vertical column, a bracket supported by the column, a support having a swivel connection with the bracket, a cutter-head sleeve capable of being clamped around the swiveled support, means for vertically adjusting the cutter-head sleeve, and 20 a cutter-spindle support pivotally connected with the cutter-head sleeve.

5. In a face mill grinder, the combination

of a base having a vertical column, a bracket supported by the column, a support having a swivel connection with the bracket, a cutter-head sleeve capable of being clamped around the swiveled support, means for vertically adjusting the cutter-head sleeve, a cutter-spindle support pivotally connected with the cutter-head sleeve, and means for 35 rocking the cutter-head sleeve and holding it when adjusted.

6. In a face mill grinder, the combination of a base having a vertical column, a bracket supported by the column, a support having a swivel connection with the bracket and 40 provided with a vertical slot, a cutter-head sleeve capable of being clamped around the swiveled support and provided with a vertical slot coinciding with the slot of the swiveled support, a cutter-spindle support 45 located within the slots of the swiveled support and cutter-head sleeve, and having a pivotal connection with the cutter-head sleeve, means for rocking the cutter-head sleeve and holding it when adjusted, and 50 means for vertically adjusting the cutter-head sleeve.

GEORGE W. SMITH.
